UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

LAMP.

1,340,163.

Specification of Letters Patent. Patented May 18, 1920.

Application filed April 29, 1919. Serial No. 293,397.

To all whom it may concern:

Be it known that I, CHARLES E. GODLEY, a citizen of the United States, and residing at Detroit, in the county of Wayne and 5 State of Michigan, have invented a new and Improved Lamp, of which the following is a specification.

This invention relates to vehicle head and spot lights and search lights for launches, 10 and its object is to provide a lamp structure which will be dust-proof, which will be noiseless when mounted on a vehicle traveling over rough roads, and which may be constructed at moderate cost.

15 This invention consists in a lamp body having a circular opening and a circumferential shoulder adjacent thereto, a reflector supported within the opening and provided with a circumferential groove which receives a packing ring, a circular lens and a lens ring made of resilient metal, and a band extending around the edge of the lens ring and the shoulder on the lamp body and adapted to pull the lens against the packing 20 ring. It also consists in so forming the lens ring that it may be sprung longitudinally of the axis of the lamp so that it may, by its resilience, secure the lens against the packing ring carried by the reflector. It 25 further consists in striking up tongues from the outer edge of the body and bending them inwardly for the purpose of supporting the reflector.

30 In the accompanying drawing, Figure 1 is a perspective of a lamp body and the reflector in place therein. Fig. 2 is a front elevation of a lamp embodying this present invention. Fig. 3 is a section on the line 3—3 of Fig. 2 on a larger scale. Figs. 4, 5 and 35 40 6 are sections on the lines 4—4, 5—5 and 6—6 of Fig. 1, respectively.

Similar reference characters refer to like parts throughout the several views.

The body 1 of the lamp is of the usual 45 parabolic form with a circumferential shoulder or rib 2 near its open end. Tongues 3, shown in section in Fig. 4, are struck up from the cylindrical outer end 4 of the body and are bent inwardly to support the radial 50 flange 5 of the reflector 6 which is preferably parabolic with a circular groove 7 formed adjacent this radial flange 5, which groove receives a packing ring 8 against which the lens 9 rests. The small tongues 55 10, shown in section in Fig. 5, are also struck up from the cylindrical end 4 of the

body and normally extend inwardly over the outer face of the radial flange 5 of the reflector, this flange being formed with notches 12 through which these tongues 10 60 pass as the reflector is turned to proper position to bring these tongues 10 out of alignment with the notches 12, and also to bring the auxiliary lamp bulb 14 into the vertical plane of the lamp.

65 The radial flange 5 is also provided with another notch into which a tongue 15, also struck up from the end 4 of the body, is bent, as shown in Fig. 6, in order to exactly position the reflector relative to the body. 70 This prevents the reflector from turning, and as the reflector is seldom if ever removed from the body, this tongue 15 is permanently positioned.

75 The lens ring 17 is circular but transversely it is arched and has an inner edge 18 engaging the lens 9. It is formed of resilient metal so that it may be sprung to carry back its rear portion 19 sufficiently to fit within the inclined flange 21 of the cylindrical locking band 22 when the other inclined flange 23 thereon engages the shoulder 2 on the body. The ends of this band have flanges 25 to receive the screw 26 which draws these ends together.

80 85 The thickness of the glass lens 9 varies but when the ring 17 is of resilient metal, it is only necessary for the edges of the inclined flanges 21 and 23 of the band 22 to at first engage the inclined shoulder 2 of the body and the inclined portion of the lens ring, for when the screw 26 is tightened, the pull of the band will spring back the outer portion of the lens ring sufficiently to permit the band to seat itself on the lamp body 90 and on the flange 19 of the lens ring, thus not only preventing the entrance of dust but also so stressing the lens ring that the lens will be tightly pressed against the packing ring 8 and the reflector will be tightly 100 pressed against the tongues 3. The tongues 10 merely hold the reflector in position when the lens is removed.

To hold the lens in its ring when not in position on the lamp body, small resilient 105 fingers 27 may be secured to the inner side of the lens ring, as shown in Fig. 3.

The details and proportions of this lamp structure may all be changed by those skilled in the art without departing from the spirit 110 of my invention as set forth in the following claims.

I claim:

1. The combination of a lamp body having a cylindrical open end and with a circumferential shoulder adjacent the open end, a lens to close the open end, a resilient metal lens ring arched in cross section and having its inner edge engaging the lens and its outer edge cylindrical, said cylindrical portion of the lens ring being of less width than the cylindrical end of the lamp body, and a locking band having a cylindrical body adapted to lie around the cylindrical edge of the lens ring and also having inwardly extending outwardly inclined flanges at its edges to engage the front of the lens ring and the rear of said shoulder on the body and force the lens ring and body toward each other.
2. The combination of a lamp body having a cylindrical open end and with an inclined circumferential shoulder adjacent the open end, a lens to close the open end, a resilient metal lens ring arched in cross section and having its inner edge engaging the lens and its outer edge cylindrical, said cylindrical portion of the lens ring being of less width than the cylindrical end of the lamp body, and a locking band having a cylindrical body adapted to lie around the cylindrical edge of the lens ring and also

having inwardly extending flanges at its edges to engage the front of the lens ring and the rear of said shoulder on the body, said flanges being inclined away from each other and adapted to fit the inclined shoulder on the body and the arched surface of the lens ring, and means to draw the band tightly around the lens ring and lamp body to force them toward each other.

3. The combination of a lamp body having a cylindrical open end and with a circumferential shoulder adjacent the open end, a lens to close the open end, a resilient metal lens ring arched in cross section and having its inner edge engaging the lens and its outer edge cylindrical and extending over the end of the lamp body, said cylindrical portion of the lens ring being of less width than the cylindrical end of the lamp body, and a locking band having a cylindrical body adapted to lie around the edge of the lens ring and having inwardly extending flanges inclined away from each other to engage the front of the lens ring and the rear of said shoulder on the body to force the lens ring toward the body when the ends of the band are drawn together, lugs at the ends of said band, and a screw engaging the lugs to draw them together.

CHAS. E. GODLEY.
